ELECTRIC DISCHARGE DEVICE

Hans Schumacher, Berlin-Lichterfelde-West, and
Heinrich Zodtner, Birkenwerder, near Berlin,
Germany, assignors to C. Lorenz Aktiengesell-
schaft, Berlin-Tempelhof, Germany

Application May 12, 1932, Serial No. 610,848
In Germany May 15, 1931

3 Claims. (Cl. 250—27.5)

This invention relates to water cooling arrangements for electron discharge tube apparatus wherein two or more electron discharge tubes are arranged to work in parallel or in push-pull connection, and more particularly to such arrangements in which the cooling water flows in parallel circuits to the water jackets of the discharge tubes over a water resistance common to the water circuits of all the jackets.

10 In arrangements of this type, if one of the anodes or one of the surrounding water jackets becomes accidentally grounded, parallel short-circuit currents flow to this point from the water jackets of all the tubes over the inlet and outlet water pipes extending to the jackets. Such short-circuit currents may easily attain a dangerous magnitude. The object of this invention is to render such short-circuits less harmful.

In accordance with the invention in a water cooling system for cooling the anodes of electron discharge tubes, in which the cooling water flows in parallel circuits to the water jackets of a plurality of discharge tubes over a water resistance common to the water circuits of all the water jackets, additional water resistances are provided between the respective inlet and outlet pipes extending to the water jackets of the different discharge tubes so that the jackets are not directly connected together electrically. With this arrangement, if an anode or water jacket becomes accidentally grounded, the total short-circuit current is substantially reduced, due to the inclusion of the additional water resistances in the short-circuits.

35 In a preferred arrangement, in which the inlet and outlet pipes extending to the water jackets are branched off from an insulating member formed with water channels and interposed between them and the water supply and outlet conduits, a part of the water channels constitutes the common water resistance and a part provides the additional water resistances.

These and other features of the invention specified in the appended claims will be better understood from the following description, reference being had to the accompanying drawing in which:

Fig. 1 is a sectioned elevation illustrating one embodiment of the invention, the representation of the electric circuits being in part diagrammatical. Fig. 2 is an elevation of a detail which is part of a second embodiment. Fig. 3 is a plan view to Fig. 2.

In Fig. 1, two electron tubes 3, 4 are shown.
55 The anodes A3, A4 thereof are cylindrical and

are each contained in a receptacle Z3, Z4. The receptacle Z3 is by a tube 2 connected with a helical channel b provided in a member 1 that consists of insulating material such as porcelain or the like. A tube 2' connects the receptacle Z3 with a second helical channel d of the member 1. The receptacle Z4 is by a tube 6 connected with the channel b and by a tube 6' connected with the channel d. The tubes 2, 2' are joined to these channels at other points than are the tubes 6, 6', so that the tubes 2, 6 are separated from each other by a portion b' of the channel b and the tubes 2', 6' likewise separated from one another, namely by a portion d' of the channel d. The channels b, d are connected with water supply conduits e and f, respectively. A direct current source A, earthed at Y, is through a resistance W3 and a choke coil D3 connected to the receptacle Z3 and through a resistance W4 and a choke coil D4 connected to the receptacle Z4. This connection is such that the receptacles Z3, Z4 are connected in parallel to the current source A. These receptacles and the tubes 2, 2', 6, 6' are electrically conductive. The anodes A3, A4 are in electric connection with that receptacle Z3 or Z4 in which they are disposed. The electron tubes 3, 4 are joined to each other in push-pull connection, as will be seen from the oscillatory circuit S. A coil C, coupled to this circuit, is part of a second arrangement that may be of exactly the same description as the one represented, and is not shown therefore.

The arrows in Fig. 1 indicate the direction in which the cooling water may be caused to flow. The water entering through conduit e flows through channel b and tubes 2, 6 into the receptacles Z3, Z4 and thence through tubes 2', 6' and channel d into conduit f. The water thus moves along the anodes A3, A4 so as to cool them.

If a grounding arises at X, for instance, then the following two circuits are established thereby, viz: A, W3, D3, Z3, X, Y, A and A, W4, D4, Z4, tubes 6, 6' in parallel, passages b', d' in parallel, tubes 2, 2' in parallel, Z3, X, Y, A. The receptacle Z3 is thus subjected to both of the currents flowing in these circuits. Owing to the water, however, contained in the channels b', d', the current in the second said circuit is decreased so that the receptacles Z3, Z4 are both subjected to a considerable smaller short circuit current than if there were no such water resistance, for instance, if the receptacles Z3, Z4 were conductively connected with each other.

The modification shown in Figs. 2 and 3 is adapted for connecting six electron tubes to the

member 1 in a like manner as that represented in Fig. 1 for two electron tubes. As shown in Fig. 2, the member 1 carries a top 9 in which twelve channels *g* are provided. This top is likewise 5 made of insulating material, such as porcelain. To these channels conduits *h* are attached in the same way as the tubes 6, 6', 2, 2', represented in Fig. 1, are attached directly to the member 1. The top 9 is thus a means for adapting the member 1 to the provision of more than two electron 10 tubes. The channels *g* can be made to be of equal lengths so as to present equal water resistances.

The arrangements here described may be altered or perfected within the scope indicated by 15 the appended claims, without departing from the spirit or sacrificing any of the advantages of this invention.

What is claimed is:

1. A water cooling system for cooling the an- 20 odes of electron discharge tubes comprising a plurality of electron tube water jackets, a set of metallic inlet pipes and a set of metallic outlet pipes connected to the respective water jackets for conducting the cooling water thereto and 25 therefrom, and an insulating member having formed therein a water channel with a plurality of multiple branches, the multiple branches of one water channel being connected to the respective pipes 20 of one of said sets and the multiple branches of another of the water channels being connected to the respective pipes of the other of said sets, each of said water channels constituting a water re- 25 sistance common to said water jackets and co-operating with the respective branches to provide water channels separating said connected pipes and constituting water resistances therebetween.

2. A water cooling system for cooling the an- 30 odes of electron discharge tubes having in combination water jackets for the anodes of said

tubes, and parallel hydraulic circuits for the flow of the cooling water to the water jackets of a plurality of electron discharge tubes comprising metallic inlet and outlet pipes connected to the jackets of the different discharge tubes and an insulating member formed with water channels connected to said pipes, part of the water channels in said insulating member constituting a water resistance which is common to the water cooling circuits of all of said discharge tubes and part 10 thereof providing a water resistance between the respective inlet and outlet pipes, whereby the water jackets of the discharge tubes are prevented from being conductively connected together over a path of low electrical resistance. 15

3. A water cooling system for cooling the anodes of electron discharge tubes comprising a plurality of electron tube water jackets, a set of metallic inlet pipes and a set of metallic outlet pipes connected to the respective water jackets for conducting the cooling fluid thereto and therefrom, and an insulating member having formed therein water channels each having a plurality of multiple branches, the multiple branches of one water channel being connected to the respective pipes 25 of one of said sets and the multiple branches of another of the water channels being connected to the respective pipes of the other of said sets, each of said water channels constituting a water re- 30 sistance common to said water jackets and co-operating with the respective branches to provide water channels separating said connected pipes and constituting water resistances therebetween.
